[57] CLAIM

The ornamental design for a connector for catheter, as shown and described.

DESCRIPTION

FIG. 1 is a perspective view of a connector for catheter showing our new design;

FIG. 2 is a front elevational view thereof;

FIG. 3 is a rear elevational view thereof;
FIG. 4 is a top plan view thereof;
FIG. 5 is a bottom plan view thereof;
FIG. 6 is a left side elevational view thereof;
FIG. 7 is a right side elevational view thereof;
FIG. 8 is a sectional view taken along line VIII—VIII of FIG. 4;
FIG. 9 is a perspective view of a connector for catheter showing a second embodiment of our new design;
FIG. 10 is a front elevational view thereof;
FIG. 11 is a rear elevational view thereof;
FIG. 12 is a top plan view thereof;
FIG. 13 is a bottom plan view thereof;
FIG. 14 is a left side elevational view thereof;
FIG. 15 is a right side elevational view thereof;
FIG. 16 is a sectional view taken along line XVII—X-VII of FIG. 12;
FIG. 17 is a perspective view of a connector for catheter showing a third embodiment of our new design;
FIG. 18 is a front elevational view thereof;
FIG. 19 is a rear elevational view thereof;
FIG. 20 is a top plan view thereof;
FIG. 21 is a bottom plan view thereof;
FIG. 22 is a left side elevational view thereof;
FIG. 23 is a right side elevational view thereof;
FIG. 24 is a sectional view taken along line XXIV—XXIV in FIG. 20;
FIG. 25 is a perspective view of a connection for catheter showing a fourth embodiment of our new design;
FIG. 26 is a front elevational view thereof;
FIG. 27 is a rear elevational view thereof;
FIG. 28 is a top plan view thereof;
FIG. 29 is a bottom plan view thereof;
FIG. 30 is a left side elevational view thereof;
FIG. 31 is a right side elevational view thereof;
FIG. 32 is a sectional view taken along line XXXII—XXXII in FIG. 28;
FIG. 33 is a perspective view of a connector for catheter showing a fifth embodiment of our new design;
FIG. 34 is a front elevational view thereof;
FIG. 35 is a rear elevational view thereof;
FIG. 36 is a top plan view thereof;
FIG. 37 is a bottom plan view thereof;
FIG. 38 is a left side elevational view thereof;
FIG. 39 is a right side elevational view thereof; and,
FIG. 40 is a sectional view taken along line XL—XL in FIG. 36.
